UNITED STATES PATENT OFFICE.

EDWIN J. HAYDEN AND EDWARD HAUSOTTER, OF MINNEAPOLIS, MINNESOTA.

BUCKLE.

1,278,340.

Specification of Letters Patent. Patented Sept. 10, 1918.

Application filed May 4, 1918. Serial No. 232,560.

To all whom it may concern:

Be it known that we, EDWIN J. HAYDEN and EDWARD HAUSOTTER, citizens of the United States, residing at Minneapolis, in 5 the county of Hennepin and State of Minnesota, have invented new and useful Improvements in Buckles, of which the following is a specification.

This invention relates to new and useful 10 improvements in belt buckles and the principal object of the invention is to provide means on the buckle for holding the free end of the strap hidden from view by the rest of the belt.

15 Other objects are to provide gripping means for removably securing the belt to the buckle and a gripping roller operating in inclined grooves for securing the free end of the belt to the buckle.

20 Another object of the invention is to provide a device of this character which is simple and durable in construction, reliable and efficient in operation and one which can be manufactured and placed upon the market at a minimum cost.

The invention also consists in certain 25 other features of construction and in the combination and arrangement of the several parts, to be hereinafter fully described, 30 illustrated in the accompanying drawings and specifically pointed out in the appended claims.

In describing our invention in detail, reference will be had to the accompanying 35 drawings wherein like characters denote like or corresponding parts throughout the several views and in which:—

Figure 1 is a side view of the invention.

Fig. 2 is a longitudinal section.

40 Fig. 3 is a rear view.

Fig. 4 is a front view.

Figs. 5 and 6 are end views.

In these views the buckle is shown at 1, the free end of the belt at 2 and the fastened 45 end at 3. The buckle consists of a plate 4 having its side edges turned downwardly as at 5. The buckle is slightly curved as shown in Fig. 1 to conform to the body and the side flanges are each provided with a 50 slot 6, said slots inclining upwardly toward the end of the buckle as shown. A roller 7 is mounted in these slots with its ends enlarged to hold the roller therein. A plate 8 is pivotally mounted in the side flanges at 55 the other end of the buckle and the edge of this plate is bent at right angles and cut to

provide teeth as shown at 9. Said teeth being so disposed that when the plate is swung against the top of the buckle the teeth will project toward said top and thus grip the belt between themselves and the buckle.

We prefer to make some of these teeth longer than the others as indicated at 12, so that the device may be used with straps of thin material. In heavy straps holes will be punched to receive said teeth.

We prefer to provide a lug or pin 10 adjacent the front edge of the buckle and extending inwardly from the inner face thereof and this pin engages holes 11 formed in the free end of the belt and acts as an additional holding means to hold this free end of the belt to the buckle.

It will be seen that the belt when used with our improved buckle may be easily adjusted to fit the person. This may be done by raising the plate 8 and cutting off a sufficient part of the belt to make the belt of the proper length and then replacing the buckle thereon by causing the plate to grip the end thereof. In using the device the free end of the belt is placed under the roller and it will be seen that the gripping plate 8 will cause the end of the belt to pass under the fastened end thereof so that the free end will be hidden from view. In carrying out this action the roller is held by the fingers at the inner ends of the slots. After the belt is in proper position the pin is placed in engagement with the proper hole and then the roller is moved toward the outer ends of the slots to coöperate with said pin in holding the free end of the belt to the buckle.

It is thought from the foregoing description that the advantages and novel features of our invention will be readily apparent.

We desire it to be understood that we may make such changes in the construction and in the combination and arrangement of the several parts, provided that such changes fall within the scope of the appended claims.

What we claim is:—

1. A belt buckle comprising a plate having side flanges, an inwardly extending pin carried by said plate adjacent one end thereof, slots in said flanges, a roller in said slots for coöoperating with the pin in holding the free end of the belt to the buckle, a plate pivoted to the first plate for engaging the other end of the belt and a part carried by said second plate for directing the free end of the belt under the fastened end thereof.

2. A belt buckle comprising a plate having side flanges, a plate having its side edges pivoted in said flanges, said plate having teeth thereon projecting at right angles thereto for gripping the end of the belt and said plate having an inclined part having its edge engaging the under face of the other plate for acting as a guide to direct the free

end of the belt under the fastened end, and means for holding said free end of the belt to the buckle.

In testimony whereof we affix our signatures.

EDWIN J. HAYDEN.
EDWARD HAUSOTTER.
